UNITED STATES PATENT OFFICE

CHARLES C. ELSTON, OF PASADENA, CALIFORNIA

TRAFFIC GUARD

Application filed August 23, 1932. Serial No. 630,120.

This invention relates to a traffic sign or guard and more particularly to a sign or guard employed for indicating safety zones, reserved or restricted territory, and lanes of travel.

In accordance with the present invention a traffic sign or guard is provided which when not in use may be lowered beneath the surrounding surface of the street out of the way, together with novel means for safety housing the sign or guard when not in use.

The invention will be best understood from a study of the following description taken in connection with the accompanying drawings 15 wherein:

Figure 1 is a top plan view showing one manner of use of the guard or sign.

Figure 2 is an elevational view of the sign in its raised position for use.

20 Figure 3 is a top plan view of the same.

Figure 4 is a longitudinal sectional view through the sign.

Figure 5 is a view taken at right angles to Figure 4 and with the sign or guard lowered 25 in out of the way position.

Figures 6 and 7 are transverse sectional views taken substantially on the lines 6—6 and 7—7 respectively of Figure 4.

Figure 8 is a perspective view of a spring 30 locking lug, and

Figure 9 is a perspective view of a handle or bail member.

With reference more in detail to the drawings it will be seen that my improved sign 35 or guard comprises a tubular casing or housing 10 that is opened at its upper end and closed at its bottom end.

Slidable in the casing 10 and adapted to be housed thereby is a post 11 that is open 40 at its bottom end and closed at its top. At the top thereof the post 11 is provided with a central depression 12 within which, when not in use, lies a bail 13 provided to facilitate raising and lowering of the post 11.

45 At its top or upper end the post 11 is also provided with an outstanding annular flange 14 provided on its under side with an annular gasket 15 of suitable yieldable material. The shoulder 15, in the post 11 is housed 50 within the casing 10 and is adapted to engage

a seat 16 provided in the upper portion of the housing or casing 10. It will be noted that the seat 16 is disposed a material distance below the surface of the ground 17 so that when the flange 14 is engaged with the seat 55 the top face of the same will be substantially flush with the surface of the roadway or pavement 17 as shown in Figure 5.

Adjacent its upper end the post 11 is provided with a circular series of relatively spaced apertures 18 and substantially closing each aperture is a reflector button 19, and each of the reflector buttons 19 is preferably colored red, and are secured in position on the inside of the post 11 as at 20.

Secured to the inner side of the post 11 adjacent the lower end of the post is a spring member 21 that has its lower end offset as at 21a and then bent inwardly at right angles as at 21b thus forming a keeper lug 70 that is normally urged outwardly of the post 11 through a vertical notch 22 provided in the lower portion of the post.

The casing 10 slightly below the middle thereof or at any other suitable point in its 75 length is provided with an aperture 23, and as shown in Figure 4 when the post 11 is raised to aline the notch 22 with the aperture 23 the lug end of the spring 21 will pass through the notch 22 and engage the aperture 23 with end 21b engaging the lower end 80 of the notch whereby the post 11 will be retained in its raised position.

It is apparent that my improved safety 85 guard or sign can be used for indicating or defining safety zones, reserved or restricted territory, and as shown in Figure 1 four or such signs or guards may be arranged at an intersection for indicating lanes of travel.

It will also be apparent, that when not in use, the posts 11 may be readily lowered into the casing 10 and fully housed thereby. Also to raise the post 11 all that is necessary is to grasp the bail 13 and pull upwardly until the keeper end 21a, 21b of spring 21 engages the aperture 23 whereupon the post 11 will be held in raised position so that the reflectors 19 will receive the rays of light emanating from the vehicle headlight of an approaching vehicle thus warning the operator that he is 95 100

approaching a signal or guard and may thereby direct his course accordingly.

Even though I have herein shown and described the preferred embodiment of the invention, it is to be understood that the same is susceptible of further changes, modifications and improvements coming within the scope of the appended claims.

Having thus described my invention, what I claim as new is:

1. In a traffic guard, a casing, a tubular post having a sliding fit within said casing, said post having at one end a wall provided with a circular recess, a bail pivoted to said wall and adapted to lie wholly within said recess, said post adjacent said one end being also provided with a circular series of relatively spaced openings, reflector buttons mounted interiorly of the post opposite said openings, a leaf spring member anchored at one end interiorly of said post and having a free end movable into and out of said post through a lateral notch provided in said post, and said casing intermediate its ends being provided with an aperture for accommodating the free end of said leaf spring, said leaf spring having said free end formed to provide a keeper engageable with the aperture in a manner to secure the post with the closed end thereof projected outwardly relative to said casing.
2. In a traffic guard, a casing open at one

end and provided at said open end with an external annular seat and an upstanding marginal flange concentric to the seat, said casing being adapted to be sunk in a pavement with the upper edge of said flange flush with the pavement, a cylindrical hollow post closed at one end, and having a snug sliding fit in the casing, said post at the closed end thereof being provided with an external recess, a manipulating bail pivoted within the recess and adapted to lie wholly within the recess, said post adjacent said closed end being also provided with a circular series of openings, reflector buttons mounted within said post in operative position to said openings, said post being also provided at its upper closed end with an outstanding annular flange adapted to engage said seat and to lie flush with the pavement, a spring keeper member having an end anchored within the post; said casing being provided with a lateral opening, and said post being provided with a lateral notch adapted to align with said opening when the post is in one position relative to said casing, and said spring latch member having an end arranged in operative position to the notch to project therethrough and engage the opening in the case to secure the post against casual rotative and axial sliding movement relative to said casing.

In testimony whereof I affix my signature.

CHARLES C. ELSTON.
